Patented Nov. 23, 1976

242,436

CASING FOR AN ELECTRONIC WATCH OR THE LIKE

Brent Nilson, San Jose, Calif., assignor to Fairchild
Camera and Instrument Corporation

Filed July 7, 1975, Ser. No. 593,338

Term of patent 14 years

Int. Cl. D10—02

U.S. Cl. D10—30

FIG. 1

FIG. 2

FIG. 3

FIG. 4

FIG. 5

FIG. 1 is a top perspective view of a casing for an electronic watch or the like, showing my new design;

FIG. 2 is a top plan view thereof;

FIG. 3 is a bottom plan view thereof;

FIG. 4 is a front elevational view thereof; and

FIG. 5 is a left side elevational view thereof, the right side being a substantially mirror image thereof but lacking the two buttons shown on the left side.

The rear elevational view thereof is substantially a mirror image of the front elevational view.

I claim:

The ornamental design for a casing for an electronic watch or the like, as shown and described.
